GLASS CHROMATOGRAPHIC TRAY UNIT

Joseph Kopp, Jackson Heights, N. Y.

Application May 18, 1955, Serial No. 36,088

Term of patent 7 years

(Cl. D16—1)

FIG. 1

FIG. 2

FIG. 3

Figure 1 is a perspective view of a glass chromatographic tray unit showing my new design;

Figure 2 is a top plan view thereof; and

Figure 3 is a transverse section taken on line 3—3 in Figure 1.

The portions shown in dotted lines are for purposes of illustration only.

I claim:

The ornamental design for a glass chromatographic tray unit, as shown and described.
